UNITED STATES PATENT OFFICE.

ELLIS F. FROST, OF PAWTUCKET, RHODE ISLAND, ASSIGNOR OF ONE-HALF
TO CHARLES H. M. BLAKE, OF WESTON, MASSACHUSETTS.

SWITCH-BOARD FOR TELEPHONE-LINES.

SPECIFICATION forming part of Letters Patent No. 237,512, dated February 8, 1881.

Application filed July 26, 1880. (Model.)

To all whom it may concern:

Be it known that I, ELLIS F. FROST, of Pawtucket, in the State of Rhode Island, have invented certain Improvements in Switch-Boards for Telephone-Lines, of which the following is a specification.

One part of my invention consists in the use, in connection with two or more telephone-circuits, of certain fixed contact plates, points, and springs and certain shifting contact-plates, of long hand-levers, in number double that of the telephone-circuits, operating the shifting contact-plates, and so pivoted that they move in parallel arcs, and that while the range of motion of the operator's hand is appreciable the actual switching mechanism is confined within a very narrow compass, thereby allowing a more compact and convenient arrangement of the switch-board than any I have heretofore known. These last-named advantages are largely due to the fact that I have devised an outwardly-curved and vertically-slotted switch-board embodying suitable contact-points, ground, signaling, and line connections, and have combined therewith switching-levers which occupy slots in said board and are movable in parallel arcs toward and from the operator, and said combination constitutes another feature of my invention.

Another part of my invention consists in the use, on a switch-board belonging to two or more telephone-circuits, of a number of hand-levers equal in number to the number of circuits, the several levers having uniform motions, and each being in electrical connection with a separate switch mechanism to bring in its own telephone-circuit, and working in a slot provided with a series of notches, the corresponding notches of the said slots being also in electrical connection with each other.

My invention consists, further, in connecting with the apparatus referred to above a single hand-telephone in such manner that the said hand-telephone may be used in the entire circuit caused by the union of any two of the telephone-circuits, or may be disconnected from them both, or may be grounded in either independently of the other, all by the use of the same hand-levers.

My invention consists, further, in connect-

ing with the switch mechanism upon a switch-board, and at a central office for connecting and disconnecting two, or two of several, telephone-circuits, independent call-circuits with suitable contact points or springs, in such manner that the same hand-levers which are used to connect and disconnect the telephone-circuits may also be used to bring in the call-circuits.

The invention consists, further, in certain details of construction, hereinafter pointed out.

In the drawings I have shown a switch-board adapted for use in connection with two telephone-circuits; but upon an examination of the numerous diagrams with which I have illustrated its use in connection with the two circuits it will appear that the number of telephone-circuits may be increased to any number. Upon examination it will appear that the apparatus shown is in two sections, one belonging to each of the two telephone-circuits, and each a duplicate of the other, excepting that the hand-telephone is directly connected to but one. For convenience, with the exception of the casing, which is common to both sections, and with the further exception of certain wires, as will appear, I have designated corresponding parts in the two sections by the same letter, adding, however, to each letter in one section a figure 1 and in the other a figure 2; or where I have found it convenient to use the same letter twice or more in each section, I have in one section added odd numerals and in the other the next even numerals.

Figure 1 is a front elevation of so much of my apparatus as is seen when inclosed in its casing, which is also shown. Fig. 2 is an inverted plan of the same. Fig. 3 is a rear elevation of the same. Fig. 4 is a section on line $x-x$ of Fig. 1, looking toward the middle of the casing. Fig. 5 is a section on line $y-y$ of Fig. 1, looking in the opposite direction. Fig. 6 is an enlarged view of a certain slot, b' , showing certain notches lined with metal, and also, in section, a certain metallic hand-lever in its normal position. Fig. 7 is a similar view of another slot, c' , with lining-plates and lever. The remaining figures consist of diagrams in explanation of the electrical circuits.

The casing, which is of wood, is in the form of the casing of a beer-pump, the hand-levers which are used for operating the switches being like the handles of a beer-pump.

5 A is the bottom of the casing; B, the front, curved in shape; C' C², the two ends, and D D' the back, the part D' being hinged to the bottom A at a a, and opening to permit the adjustment of apparatus within. The curved 10 front B has two long slots, b' b², through which work two brass levers, F' F², which are pivoted to the bottom A, within the casing, as shown, and two shorter slots, c' c², through which, in the same manner, work two brass 15 levers, E' E², whose inner ends are rigidly secured to two wooden quadrants, G' G², which are pivoted to the bottom A, slots d' and d² permitting movements of the quadrants corresponding to the movements of the levers E' 20 and E² in the slots c' and c². The long slot b' has four notches, e' e³ e⁵ e⁷, which are in part or wholly lined with brass, and the slot b² has four corresponding brass-lined notches, e² e⁴ 25 e⁶ e⁸. The long slots b' and b² have also, respectively, for a lining at the head of the slots, short brass plates, e⁹ and e¹⁰. The shorter slots c' and c² have respectively upon one side, as a lining, a long brass plate, f' f², and a short brass plate, f³ f⁴. The quadrant G' has upon 30 one face, near its curved edge, a long brass strip, g', and a short brass strip, g⁵, the latter being wrapped around the lower edge of the quadrant, so as to extend an equal distance up the opposite face. Upon this opposite face is a long brass strip, g⁵, being, however, not quite as long as strip g', there being on this face, above the strip g⁵, a short strip, g⁷, which extends also partially across the rear edge of the quadrant.

35 40 Confining the description for the present to one section of the instrument, H' is a long metallic spring, one end of which is secured to the inside of the back of the casing, while the other presses always upon the strip g', whatever may be the position of the quadrant G'.

J' is a short metallic spring, one end of which is secured to the bottom A, while the other presses always against the quadrant G' upon the same side as the spring H', being either in 45 contact with strip g⁵ or strip g', according to the position of the quadrant. K' is a long metallic spring, secured to the back of the casing and pressing always upon the opposite face of the quadrant G', and, according to the 50 position of the latter, being either in contact with strip g⁵ or strip g⁷; and pressing upon the same side of the quadrant G' with spring K', and secured to the bottom A, is a short spring, S', in contact either with strip g⁵ or strip g⁷, according to the position of the quadrant. In 55 the other section, respectively corresponding to the parts H', g', J', g³, K', g⁵, g⁷, and S', and used in connection with the quadrant G², are precisely similar parts, (not shown, however, excepting in the diagrams,) H², g², J², g⁴, K², g⁶, g⁸, and S².

60 L', M', N', O', P', Q', and R' are binding-screws 65 in section 1 in immediate connection with apparatus worked by hand-levers E' and F', while L², M², N², O², P², Q², and R² are similar binding-screws in connection with apparatus worked by hand-levers E² and F² in section 2. In the bottom of the casing in section 1 are four holes, j', j³, j⁵, and j⁷, while in section 2 are four holes, j², j⁴, j⁶, and j⁸. A wire, w', connects notch e' in slot b' with notch e² in slot b², the said wire in its passage passing through holes j' and j². (This wire and all other wires to which reference is made in this description are shown only in the diagrams; and this is true, also, of hand-telephones, call-bells, batteries, distant stations, and grounds.) In like manner wire w² connects notches e³ and e⁴, passing through holes j³ and j⁴. Wires w³ and w⁴ make similar connections. Other electrical connections are 80 as follows: Binding-screws O' O² are in electrical contact, respectively, with brass lining-plates e⁹ and e¹⁰ at the head of slots b' and b². Binding-screws M' and M² are in contact with long springs K' and K². Binding-screws L' and L² are in contact with long springs H' and H². Binding-screws P' and P² are respectively connected by wires v' and v² with hand-levers E' and E². Binding-screws N' and N² enter the slots c' and c², in order that the hand-levers E' 85 and E² may at times be pressed against them, these hand-levers being so sprung that in their upper normal positions they do not touch binding-screws N' and N². Wire w⁵ connects binding-screw L' with binding-screw L², and wire w⁶ connects binding-screw M' with binding-screw M². A hand-telephone, T, is placed 90 in section 1 on a wire, t, connecting binding-screws L' and M'. This single hand-telephone, as will hereinafter appear, is used for all the sections. A wire, o', passing through a call-bell, connects binding-screw O' with the ground, and in like manner a wire, o², passing through another call-bell, connects binding-screw O² with ground. A line-wire, l', passes from binding-screw P' through all the stations of 95 section 1 to ground, and in like manner a line-wire, l², passes from binding-screw P² through all the stations of section 2 to ground. Binding-screw Q' is grounded by wire q', and binding-screw Q² is grounded by wire q². A wire 100 y', connects brass lining-strip f' with spring J' in section 1, and wire y² connects f² with J² in section 2. Wire z' connects short brass lining-strip f³ with binding-screw R', and wire z² connects f⁴ with R². Wire r' connects hand-lever F' with spring S', and wire r² connects hand-lever F² with spring S².

The manner of operating this apparatus, its conveniences and advantages, are shown in the 105 diagrams, where, unless otherwise stated, similar letters refer to parts designated by like letters in the other figures. For clearness in illustration, however, I have substituted for the quadrants having brass strips upon two faces 110 and working between two sets of springs straight bars with four contact-strips, each upon a single face; and, placing the springs at a little distance, I have represented the shift-

ing contacts between strips and springs by broken lines, as will readily appear.

The operation is as follows:

1. In the normal condition of the apparatus all the hand-levers E' , E^2 , F' , and F^2 are up, E' and E^2 being in contact, respectively, with the upper ends of the lining-plates f' f^2 in slots c' c^2 , and F' and F^2 being in contact, respectively, with plates e^9 e^{10} in slots b' and b^2 .
- 10 The circuit at section 1 is from out-stations belonging to that section, by wire l' , binding-screw P' , wire v' , hand-lever E' , lining-plate f' , (in slot c') wire y' , spring J' , strip g^3 , spring S' , wire r' , hand-lever F' , plate e^9 , (in slot b'), binding-screw O' , wire o' , through call-bell belonging to section 1, to ground. This is the calling-circuit for out-stations on telephone-line belonging to section 1. For section 2 there is a precisely similar circuit, which may be easily traced in diagram 4, although a different condition of the apparatus is there shown, a different circuit having been there established. In the normal condition of the apparatus the two telephone-circuits are not connected.
- 25 2. A person at an out-station belonging to section 1 having called the central station, the operator at the central station pulls the hand-lever E' about half-way down in slot c' . This establishes a telephone-circuit, as shown in diagram 2—viz., from ground at central station, by wire o' , to binding-screw O' , brass plate e^9 , hand-lever F' , by wire r' to short spring S' , to strip g^5 , (on quadrant G'), long spring K' , binding-screw M' , through the telephone T to binding-screw L' , long spring H' , strip g' , (on quadrant G'), small spring J' , by wire y' to long lining-plate f' , (in slot c'), hand-lever E' , by wire v' to binding-screw P' , through the out-stations of section 1 to ground.
- 30 3. A similar telephone-circuit for section 2 can be easily traced by reference to diagram 4, although the diagram is not drawn to illustrate this circuit, the connections shown being for another purpose—that is, if a person at an out-station in section 2 has called the central station, the operator pulls the hand-lever E^2 half-way down in slot c^2 , and the circuit is from ground at central station, by wire o^2 , to binding-screw O^2 , plate e^{10} , hand-lever F^2 , wire r^2 , spring S^2 , strip g^6 , spring K^2 , binding-screw M^2 , wire w^6 , binding-screw M' , hand-telephone T , binding-screw L' , wire w^5 , binding-screw L^2 , spring H^2 , strip g^2 , spring J^2 , wire y^2 , plate f^2 , hand-lever E^2 , wire v^2 , binding-screw P^2 , and out-stations to ground.
- 35 4. The person at the out-station who has called the central station, speaking through his telephone, makes known the other out-station with which he wishes to be put in communication; and for the present it is supposed that this second out-station belongs to section 2. The operator at the central station, leaving the E hand-lever of the section of the party calling—that is, in this instance E' —in the position shown in diagram 2, brings down the F lever of the party calling—that is, in this instance F' —and places it in any notch whose corresponding notch in any other section upon the switch-board is not occupied—say in e' (see diagram 4)—and then calls the party in section 2 who is wanted by pressing hand-lever E^2 against binding-screw N^2 a number of times corresponding to that party's number in the section. This calling-circuit is from ground, through calling-battery at central office, to binding-screw N^2 , hand lever E^2 , wire v^2 , binding-screw P^2 , to out-stations, (including bell-circuits at out-stations,) and ground. The hand-lever E^2 springs back to its normal position at the top of lining-plate f^2 when not forced against the binding-screw N^2 .
- 40 5. The operator at the central station, after ringing up the party in section 2, leaving the hand-levers E' and F' of section 1, which is the section of the calling party, in the positions last stated—that is, at the positions shown at section 1 in diagram 4—brings down hand-lever F^2 and places it in the notch of slot b^2 corresponding to the notch in which he has placed F' —that is, in this instance, in notch e^2 ; but the operator leaves hand-lever E^2 undisturbed—that is, leaves it up. The circuit is then from ground, through out-stations of section 1 by line-wire l' , to binding-screw P' , by wire v' to hand-lever E' , strip f' , (in slot c'), by wire y' , spring J' , brass strip g' , spring H' , binding-screw L' , telephone T , binding screw M' , spring K' , strip g^6 , spring S' , wire r' , hand-lever F' , notch e' , by wire w' (passing through holes j' j^2) to notch e^2 , hand-lever F^2 , wire r^2 , spring S^2 , strip g^4 , spring J^2 , wire y^2 , strip f^2 , (in slot c^2), hand-lever E^2 , wire v^2 , binding-screw P^2 to out-stations and ground.
- 45 6. If, when connection has been thus made, the party called does not answer, he may be called again by simply pressing hand-lever E^2 against binding-screw N^2 . It is obvious that the combined circuit just described is but momentarily disturbed, for when hand-lever E^2 is left free it springs back, as before stated, to lining-plate f^2 .
- 50 7. If answer is made, the operator at the central station cuts his own telephone out by placing the rod E in its normal position—i.e., upright. The circuit between the communicating parties is then, as shown in diagram 5, from ground and out-station to binding-screw P' , wire v' , hand-lever E' , lining-plate f' , wire

y' , spring J' , strip g^3 , spring S' , wire r' , and on as before in diagram 4.

In the same manner as it was shown that a telephone-circuit might be established between 5 a section 3 and the hand-telephone, which is located in section 1, it might be shown that a telephone-circuit might be established between a section 4 and the same telephone, it being sufficient to say that a wire runs through 10 all the L binding-screws—*i. e.*, $L' L^2 L^3 L^4 L^5$, &c.—and another wire through all the M binding-screws—*i. e.*, $M' M^2 M^3 M^4 M^5$, &c.; and it is obvious that the hand-telephone might be located at any other station as well 15 as at station 1, except that it is convenient to have it at the right of the casing. It only remains to add that in like manner all the corresponding notches in the b slots—*i. e.*, in the slots $b' b^2 b^3 b^4 b^5$, &c.—are connected by a 20 wire running through them all, and it follows that by placing any two of the F levers—*i. e.*, any two of $F' F^2 F^3 F^4 F^5$, &c.—in corresponding notches of their respective slots, any two sections may be connected. There should be 25 as many notches in each b slot as there are b slots on the switch-board.

In diagram 3^a I have represented the manner in which a magneto-call may be connected and used by the operator at the central station—that is, the lining-plate f^4 is in electrical connection with binding-screw R^2 , which is connected, as indicated, with a magneto-generator and ground. To use the magneto-call the operator, instead of pressing the hand-lever 30 E^2 against binding-screw N^2 , as before directed, brings it down into contact with lining-plate f^4 , when the magneto circuit is established, as indicated in diagram 3^a. When, therefore, the apparatus is constructed, as shown, so that 35 the quadrants have four strips, it may be used either with a call-battery, as represented in diagram 3, or with a magneto-generator, as represented in diagram 3^a. The short strips at the top of the quadrants g^7 and g^8 are used 40 for grounding their respective telephone-circuits, the grounding binding-screws Q' and Q^2 being electrically connected with them, as before stated. The hand-telephone at the central office is brought into the circuit, which is thus 45 grounded. The advantage of this is that when a connection has been established between two sections the hand-telephone may be used in the telephone-circuit of either of them by simply bringing down the E hand-lever in that 50 section to the lower end of the long lining-plate of its slot, (see diagram 6,) and then the connection may be restored by simply raising the same hand-lever. If, therefore, the operator observes that a third party has broken 55 60 in, he uses this branch of the switch to request that party to withdraw. So far as the switch-board is concerned the connection is at no time essentially disturbed.

It may be well to add that all N binding-screws are grounded through a battery and all O binding-screws are grounded through a call-bell. All P binding-screws are grounded

through the out-stations of the sections to which they respectively belong. All Q binding-screws are simply grounded.

Each F lever is furnished with a spring, as shown in Fig. 4, which causes it to assume its normal position when released from an e notch.

I claim—

1. With two or more telephone-circuits, suitable contact plates and points, (fixed and movable,) connecting-wires, and a switch-board, the combination in each circuit of two switching hand-levers, respectively, for connecting lines and for grounding or signaling, or both, and 75 working in parallel arcs on said switch-board, substantially as described.

2. The outwardly-curved vertically-slotted switch-board, embodying suitable contact points, ground and line connections, in combination with switching-levers which occupy 85 slots in the curved board and are movable in parallel arcs toward and from the operator, substantially as described.

3. On a switch-board belonging to two or 90 more telephone-circuits, the combination, with separate switching mechanism, of a number of switching hand-levers equal to the number of circuits, the several levers having uniform motions, and each being in electrical connection 95 with said separate switch mechanism to bring in its own telephone-circuit, and working in a slot provided with a series of notches, the corresponding notches of said slots being also in electrical connection, substantially as described.

4. With two or more telephone-circuits, the combination of a switch-board and a number of switching hand-levers equal to the number of circuits, the said hand-levers being located 105 upon said switch-board, which is common to them all, and each working in a slot provided with a series of notches, the corresponding notches of said slots being in electrical connection, substantially as described.

5. The combination, substantially as herein-before described, of switching hand-levers for connecting and disconnecting two, or two of several, telephone-circuits, and independent call-circuits having points or springs for contact with the switching hand-levers, whereby 115 these latter are available for bringing in the call-circuit as well as for connecting and disconnecting the telephone-circuits.

6. The combination, substantially as herein-before described, of two or more switching-levers working in parallel slots on a switch-board, and each connected with its own telephone-circuit, electric connections for connecting one lever with another, a call-battery at 125 the central office, and electric connections for connecting either of said levers with the call-battery, whereby, when telephone-circuits have been connected, the call-battery may be brought in with but momentary disturbance of the connected telephone-circuit.

7. Two or more telephone-circuits and a switch-board provided with contact points and plates, fixed and movable, connecting-

wires, and a pair of switching hand-levers for each circuit, co-operating substantially as described, in combination with a single hand-telephone at a central office, connected with 5 line and ground by means of the switching-levers, substantially as described, whereby the single telephone may be used in any entire circuit formed by the union of two or any two of

the telephone-circuits, or disconnected therefrom, or grounded in any one circuit independently of another, by working the hand-levers appropriate to said circuit.
